UNITED STATES PATENT OFFICE.

JEAN JACQUES FERNAND BALÉS, OF TALENCE, FRANCE.

DRYING APPARATUS.

1,166,311.

Specification of Letters Patent. Patented Dec. 28, 1915.

Application filed March 5, 1914. Serial No. 822,650.

To all whom it may concern:

Be it known that I, JEAN JACQUES FERNAND BALÉS, a citizen of the French Republic, residing at Talence, Gironde, in France, have invented certain new and useful Improvements in Drying Apparatus, of which the following is a specification.

This invention relates to improvements in drying apparatus.

Drying apparatus is known wherein the circulation of the air in the drying chamber is produced by rotary fans arranged in the drying chamber and adapted to suck air into said chamber, steam pipes being arranged within said chamber opposite the fans for the purpose of heating the inflowing air.

The present invention comprises a drying chamber comprising the above known drying means and especially designed for drying confectionery and in particular gum lozenges.

In the improved chamber the fans are arranged opposite one another and have a diameter of action extending substantially over the whole height of the chamber so that articles can be efficiently and evenly dried at any point in the chamber, which is of importance in the manufacture of lozenges or pastils as the same can be placed on trays arranged close together and ranging through the entire height of the chamber.

The annexed drawing illustrates an example of construction of the invention, in which—

Figure 1 is a front elevation of the apparatus. Fig. 2 is a side view thereof. Fig. 3 is a transverse section thereof, and Fig. 4 a longitudinal section.

The apparatus comprises a chamber constituted by double walls *a* of wood or other suitable material, between which is a suitable heat insulating material, agglomerated cork for example. The chamber has preferably no bottom and rests directly on the ground. A door *b* comprising double walls allows of hermetically closing the chamber, and in the roof is an opening *c* closed by a hollow bung *c'* containing an insulating material. Inside and preferably on the lateral walls of the chamber are mounted two ventilating fans *d* and *e* which are rotated by means of pulley and belt or other gearing *f* from a shaft *f* arranged externally of the chamber and driven by suitable power, the

transmission gearing being outside the chamber.

The entrance of air during the action of the fans is effected through lateral openings *g*. Opposite each fan radiators *h*, *i*, 60 are arranged comprising disks, or heat radiating plates, the said radiators being heated by steam by means of a pipe *j* connected to each of them. A cock *k* is provided for regulating the supply of steam 65 and consequently the degree of heat in the chamber, the interior temperature being indicated exteriorly by a thermometer *l*.

Inspection doors *m*, *n* allow of ascertaining the progress of the drying operation. 70 Evacuation of the products of evaporation is effected through two orifices *m'*, *n'*, arranged at the lower part of each of the longitudinal sides of the chamber, the two orifices at each side being connected exteriorly by the pipes *o* which are connected by vertical conduits *p* to a central pipe *r* conveying the products of evaporation outside. By making the outlets *m'*, *n'*, at the lower part of the chamber the heavy air, 80 that is to say, the most humid air is only evacuated.

The air saturated with moisture being expelled from the chamber by the operation of the fans, the question of density cannot prevent its evacuation, since during the operation of the apparatus the upper opening *c* being closed, it will be forcibly expelled through the lateral conduits *p* connected to the central conduit *r*. The air thus expelled is replaced by the outer air arriving through the opening *g* leading out at the center of the fan and which could not be thus submitted to the action of the vanes of the fan and passes freely into the chamber.

By the rotary movement of the fans, the air is agitated in all directions and perfect drying is obtained, which is rapid and equal throughout the capacity of the chamber. The products to be dried can consequently 100 be placed at any height in the chamber, so that the substances or articles to be dried can be placed on frames *q* mounted on wheels *q'* shown in dotted lines or on other carriages which can be introduced into the 105 chamber and withdrawn when drying is complete. The apparatus illustrated is shown containing two carriages, but it may be constructed to take a larger or smaller number.

The object of the aperture *c* is to obtain a supply of cold air through the exhaust pipe *r* to maintain the drying of the products in course of desiccation.

- 5 Certain products to be dried such as gum pastils require a minimum of thirty-six hours before being perfectly dried. These pastils being molded in impressions made in starch powder would not stand remaining 10 several hours in an atmosphere saturated with moisture. The starch powder would form a crust around the pastils and these would be lost. On stoppage of the fans during nonworking, the air saturated with moisture freed by the evaporation could not be conducted to the exterior through the pipes *p* and *r* but if the orifice *g* serving for the supply of air during working is closed, and the bung *c* is opened, the hot air passing 15 out through this orifice, cold air will be drawn through the pipe *r* thus following, but in the contrary direction, the same path as the air evacuated during working. This cold air will consequently traverse the products being dried, from below upward and will escape through the bung *c* thereby carrying out with it the moisture as it is disengaged. Since after stopping the introduction of steam into the radiators, the temperature remains high for a long time in 20 the chamber by reason of its insulated walls, the drying will continue under good conditions and for gum pastils in particular their deterioration would not have to be feared 25 by reason of the adherence of the starch powder.

The improved drying chamber is principally intended for use in the manufacture of confectionery and in particular in the 30 manufacture of gum lozenges and other pastils requiring drying. It can however be equally well employed for drying any other products. By reason of its insulated sides a high degree of temperature 35 can be maintained and the temperature is equal throughout the chamber. The ap-

paratus requires little expense for heating and can be easily displaced. Several chambers can be juxtaposed and their fans driven by means of the same shaft.

50

What I claim as my invention and desire to secure by Letters Patent of the United States is:—

1. Drying apparatus comprising in combination a chamber having an air inlet, heating elements disposed in said chamber and fans disposed therein adapted to force air over said heating elements, said fans being positioned at opposite sides of said chamber and having a diameter or range 55 of action, substantially equal to the height of said chamber.

2. Drying apparatus comprising in combination a chamber, heating elements disposed therein, rotary fans disposed in said 60 chamber adapted to force air over said heating elements, said fans having bearings in the wall of said chamber at opposite sides thereof, and having a diameter or range of action substantially equal to the height of 65 said chamber and means for inlet of air to said chamber positioned adjacent the bearings for said fans.

3. Drying apparatus comprising in combination a chamber, having means for inlet of air through its walls, heating elements disposed in said chamber, fans disposed in said chamber adapted to force air over said heating elements, said fans being positioned at opposite sides of said chamber and having a diameter or range of action 70 substantially equal to the height of said chamber and means at the lower part of the chamber for evacuation of products of evaporation therefrom.

85

In witness whereof I have signed this specification in the presence of two witnesses.

JEAN JACQUES FERNAND BALEÉS.
